CEMETERY MEMORIAL PLAQUE OR THE LIKE

Robert J. Rettman, Pittsburgh, Pa., assignor to Jas. H. Matthews & Co., Pittsburgh, Pa., a corporation of Pennsylvania

Application December 3, 1956, Serial No. 44,041

Term of patent 14 years

(Cl. D79—2)

Fig. 1

The characteristic feature of my design for the memorial plaque disclosed resides in the specific floral pattern at the base of the vase as shown.

I claim:

The ornamental design for a cemetery memorial plaque or the like, substantially as shown and described.
